DIAPER AND SHIRT CLASP

Fred Sherwood Clark, New York, N. Y., assignor to
 Ryan Jewelry Corporation, a corporation of
 New York

Application January 10, 1944, Serial No. 517,759

6 Claims. (Cl. 24—81)

My invention relates to garment clasps and especially to diaper clasping means for securing a baby's diaper about the infant and to means for attaching the baby's diaper to the infant's undershirt.

The present device for securing a baby's diaper in position is the metal safety pin. This has always been regarded as a physical hazard due to the possibility of accidentally opening the pin with injury to the infant. Moreover safety pins have been accidentally swallowed with attendant injuries. A more recent development is the need for some device of a non-metallic nature to replace metal due to war requirements.

The principal objects of my invention are therefore to provide a safety clasp for a baby's diaper that will securely fasten with a lock as many folds of a baby's diaper as desired; which has no sharp edges and which can not therefore injure the child when the clasp is open; which may be non-metallic in composition, and therefore rust-proof, sanitary and not cold to the touch, as is metal; which is preferably made of a plastic material; which is sufficiently large to prevent accidentally swallowing the clasp; which may be provided with additional attaching means for securing the diaper to the child's undershirt; and which has a certain flexibility longitudinally of the clasp to accommodate varying thicknesses of material.

Additional objects are to provide such a clasp, that is easy to manufacture, inexpensive in cost, and which is sufficiently durable to withstand normal strains and wear and tear.

I accomplish these and other objects and obtain my new results as will be apparent from the device described in the following specification, particularly pointed out in the claims, and illustrated in the accompanying drawing, in which:

Fig. 1 is a top plan view of my device.

Fig. 2 is a bottom plan view of the same.

Fig. 3 is a perspective view in open position.

Fig. 4 is a longitudinal cross-section of the device shown in Fig. 1 through the plane 4—4, with the device open, as in Fig. 3.

Fig. 5 is a sectional view with the diaper and baby's shirt secured to my device, taken through 5—5 of Fig. 8.

Fig. 6 is a transverse view through the locking device, of Fig. 5, through plane 6—6.

Fig. 7 is a transverse view through the shirt locking means of Fig. 5, through plane 7—7.

Fig. 8 illustrates a front view of my device in position on the baby's diaper, attached to the undershirt, on the side of the baby.

Referring to the drawing reference numerals 10 and 11 designate a pair of jaw members pivotally mounted as at 12. Any pivoting or bearing arrangement can be used, a hinge being shown by way of illustration. A button 13, provided with flattened heads 14 and 15, and shank 16, provides the means for locking the two jaw members in position about the baby's diaper.

Undershirt attaching-means consist of the loop member 17 with central wedge member 18, all pivoted at the common hinge 12. Jaw member 10 is slotted as at 19, into which slot, button shank 16 is longitudinally movable. The slot extends to the hinged end of jaw member 10 forming the open portion of U-shaped extending arms 20 and 21 through which, bores 22 and 23 respectively are formed for the hinge pin 12. The button 13 is inserted into the open slot 19, before assembling of the jaw to the hinge, there- 10 by mounting the button in the slot, the heads 14 and 15 of the button being larger than the slot to prevent dislocation. The jaw member 10 terminates in a centrally formed claw 24, which projects at right angles to the jaw member 10, 15 to insure a good hold on the material inserted between the jaws.

The other jaw member 11 is similarly slotted at 25 which slot is widened at the hinged end, as at 26, to enable the head 14 of the button 13 to be pushed therethrough as shown in Figs. 1 and 2 the shank 16, shown in Fig. 4, of sufficient length to permit such insertion. The widened opening 26 of the slot 25, forms the outer U-shaped arms 27 and 28 to extend to the hinge, the arms 20 and 21 fitting therein, so that both jaw members can be pivoted at the same hinge pin. Bores 29 and 30 are formed in arms 27 and 28 respectively for this purpose. Jaw member 11, terminates in a pair of extending claws 31 and 32, with a cut-out 33, inbetween to permit claw 24 of jaw member 10 to be positioned therein when the jaw members are locked, with sufficient space between claws to permit the material to be caught inbetween.

On the surfaces of the two jaw members upon which the heads 14 and 15 of the button 13 rides, special means are provided for locking the button in the closed position. One means consists in forming a shoulder 34 adjacent the enlarged opening 26 of the slot 25 in jaw member 11 which prevents the head 14 of the button 13 from falling back into the opening 26. Additionally the outer surface is inclined upwardly as at 35 to permit the button head 14 to ride until the desired pressure is obtained.

On the jaw member 10, a seat 36 is provided for keeping the button head 15 in closed position.

A certain resiliency found in plastic may be present in the jaw members 10 and 11 to enable the jaw members to accept fabric of varying thicknesses in the space between the two jaws. The button is moved to locked position under resilient pressure which together with the seat 36 will maintain the button in position when the jaws are locked.

Between the U-shaped arms 20 and 21 of the jaw 10 is disposed the loop member 17, with the two ends of the loop designated as 37 and 38 respectively. These ends are bored as at 39 and 40 to provide pivot support for the hinge 12. The head 41, of wedge member 18 is similarly provided with a base 42 for the hinge, and extends into the open portion of loop member 17. As seen in the cross-sectioned view of Figs. 5 and 7 the head has a wedging action for forcing the material of the undershirt 43 between the loop 17 and the head 41, and wedging it securely in position. A small projection 44 may be provided on the edge of the head 41 to provide an added lock. The loop 17 and wedge member 18 may be omitted from the construction where only the diaper clasp is desired.

To facilitate the wedging action the legs 33 and 37 of the loop 17 may be recessed as at 46 and 47 respectively to allow for the thickness of material reaching almost to the hinge. In the wedging action, the head 41 may be diamond faced as at 48 (see Fig. 5) to resist removal.

In Fig. 8, the two layers of the diaper 50 are shown overlapped to secure the diaper in position about the body of the infant, with the shirt thereof locked thereto.

The foregoing construction may be entirely made of plastic material which possesses the desired degree of durability combined with a certain flexibility in the gripping sections to enable the locking means to be applied and secured to varying thicknesses without injury. The pivoting of all the parts about a common point makes for a simplicity of construction facility manufacture and reducing the cost.

In its open position any desired thickness material may be inserted therein without interference from the parts, the button being adjacent the pivot. The device is conveniently locked and opened by action of the thumb, without injury to parts or material.

The garment clasp may be used for a variety of purposes, such as: supporting hose to an elastic strip, trousers to a shirt as a suspender clasp, etc. Other well known attaching means may be associated with the jaw members and associated locking means for these purposes.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained, and new results accomplished, as it is obvious that the particular embodiments herein shown and described are only some of the many that can be employed to attain these objects and accomplish these results.

What I claim and desire to secure by Letters Patent, is as follows:

1. A garment clasp comprising a pair of pivoted jaw members with pivoting portions and having terminal garment engaging portions and provided between the garment engaging portions and the pivoting portions with longitudinal slots, a locking button with a shank and a head at each end longitudinally slidably mounted on one jaw member with its shank extending through the slot thereof and its heads at opposite faces of said jaw member and larger than the slot thereof, the other jaw member having an enlarged opening at the end of the slot adjacent the pivoting portions opposite the slot of said other jaw member for receiving one of the heads of said locking button for locking the two jaw members together by movement of the locking button away from the pivoting portions.
2. A garment clasp comprising a pair of pivoted jaw members with pivoting portions and having terminal garment engaging portions and provided between the garment engaging portions and the pivoting portions with longitudinal slots, a locking button with a shank and a head at each end longitudinally slidably mounted on one jaw member with its shank extending through the slot thereof and its heads at opposite faces of said jaw member and larger than the slot thereof, the other jaw member having an enlarged opening at the end of the slot adjacent the pivoting portions opposite the slot of said other jaw members for receiving one of the heads of said locking button for locking the two jaw members together by movement of the locking button away from the pivoting portions, one of said jaw members being provided with a seat arranged to receive one of the heads of said locking button for holding the said button in locked position.
3. A garment clasp comprising a pair of pivoted jaw members with pivoting portions and having terminal garment engaging portions and provided between the garment engaging portions and the pivoting portions with longitudinal slots, a locking button with a shank and a head at each end longitudinally slidably mounted on one jaw member with its shank extending through the slot thereof and its heads at opposite faces of said jaw member and larger than the slot thereof, the other jaw member having an enlarged opening at the end of the slot adjacent the pivoting portions opposite the slot of said other jaw member for receiving one of the heads of said locking button for locking the two jaw members together by movement of the locking button away from the pivoting portions, one of the jaw members having a shoulder arranged to be engaged by the button for preventing the button head from entering the enlarged opening.
4. A garment clasp comprising a pair of pivoted jaw members with pivoting portions and having terminal garment engaging portions and provided between the garment engaging portions and the pivoting portions with longitudinal slots, a locking button with a shank and a head at each end longitudinally slidably mounted on one jaw member with its shank extending through the slot thereof and its heads at opposite faces of said jaw member and larger than the slot thereof, the other jaw member having an enlarged opening at the end of the slot adjacent the pivoting portions opposite the slot of said other jaw member for receiving one of the heads of said locking button for locking the two jaw members

together by movement of the locking button away from the pivoting portions, one of the jaw members having a shoulder arranged to be engaged by the button for preventing the button head from entering the enlarged opening and the other jaw member being provided with a seat arranged to receive one of the heads of the button for holding the button in locked position.

5. A garment clasp comprising two pivoted jaw members, each of said jaw members having a garment engaging portion at one end, means for securing the jaw members in closed position in engagement with a garment, and auxiliary attaching means at the other ends of the jaw members and comprising a looped section carried by one of the jaw members and composed of spaced sides and a transverse portion connecting the outer ends of said sides, and a central section positionable within the looped section by closing movement of the jaw members, the outer periphery of the central section being spaced from the

inner periphery of the looped section to allow material to be placed therebetween and to be wedged therein when the central section enters the looped section.

5. A garment clasp comprising a pair of pivoted jaw members, each having a garment engaging portion at one end, locking means slidably mounted on one of the jaw members between the pivoted portion thereof and the garment engaging portion for slidable movement longitudinally of said jaw member toward and from said pivoted portion, and cooperating locking means on the other jaw member for locking engagement with the first mentioned locking means and disengagement therefrom by said sliding movement of said first mentioned locking means, the jaw member when unlocked having pivotal movement unrestricted by said locking means.
